DISCLOSING SOLUTION

David V. Bender, Youngstown, Ohio

No Drawing. Application April 5, 1937,
Serial No. 135,076

7 Claims. (Cl. 167—93)

This invention relates to a disclosing solution for application to the teeth to render visible the mucin or bacterial plaques or deposits of other foreign material on the teeth which form stains on the teeth. These plaques are not readily visible and unless treated with a disclosing solution, are likely to be overlooked when the teeth are cleaned. They lead to decay of the teeth and should therefore be removed.

Disclosing solutions which have been used heretofore contain iodin in an inorganic compound as an essential ingredient. These inorganic iodin-containing disclosing solutions are objectionable for several reasons, and because of their disadvantageous properties have not attained the wide use which it is desirable that disclosing solutions should have in the cleaning of teeth. Iodin, as is well known, is poisonous and precautions must therefore be taken not to leave this type iodin-containing disclosing solutions in places where they are accessible to children. My disclosing solution, on the contrary, is non-poisonous. Iodin is irritating to the soft tissues of the mouth, and if used in excess, it will cause burning or blistering of these tissues. Some people have iodin idiosyncrasies, that is, a susceptibility to iodin, which renders its use on such persons inadvisable. It may actually cause a poisoning of such people. Cases are known where a person has been so susceptible to iodin poisoning that it has been necessary for him to carry a card with him warning against the use of iodin in the event that he is injured. In addition, disclosing solutions containing inorganic compounds of iodin have a disagreeable taste which prevents their being widely used.

These deleterious properties of iodin-containing disclosing solutions are obviated in the disclosing solution of the present invention, which contains a non-poisonous organic dye or mixture of such dyes as the essential ingredient. My disclosing solution is preferably an aqueous solution containing Guinea Green B ($C_{37}H_{35}N_2O_6S_2Na$) and Rose Bengal ($C_{20}H_4O_5Cl_2I_4Na_2$). Although the Rose Bengal of this disclosing solution contains some iodin, it constitutes only a small percent of the dye and is in a non-ionized form. Since the iodin is not in the ionized form and not free, none of the above objectionable properties of prior known disclosing solutions containing iodin and its compounds in inorganic form are noticeable in my disclosing solution. The solution may, however, contain only one of these dyes, but it is preferred that it contain both. The use

of both of these dyes in the disclosing solution gives a more pronounced color reaction with the stains on the teeth than either one alone. Guinea Green B is one of the permitted coal tar food dyes (United States Department of Agriculture, Bulletin No. 1390, page 10, revised December 1927). Rose Bengal is a harmless organic color (Leach-Winton, Food Inspection and Analysis, 4th edition, page 815).

Guinea Green B, a triphenylmethane dye, is made by condensing benzylethylanilinesulphonic acid with benzaldehyde, followed by oxidation of the resulting compound and conversion into the monosodium salt. It is a dull dark-green powder or bright crystalline solid which dissolves in water to form a green solution. Rose Bengal is a sodium or potassium salt of tetra-iodo-dichlorofluorescein. It is a brownish or red powder which is readily soluble in water, yielding a cherry-red color.

The disclosing solution preferably contains an agent for increasing the viscosity, in addition to the organic dye or dyes and water. The preferred thickening agent is glycerine, although gelatinous or other materials which have the property of thickening aqueous solutions may be employed. It is desirable, although not absolutely necessary, to employ a thickening agent in order that the disclosing solution will have the proper viscosity so as to remain on the teeth for a sufficient time to react with the stain.

In addition to the ingredients specified, it is also desirable to employ a small amount of acetic acid. The acetic acid appears to intensify the color reaction with the stains on the teeth. A less satisfactory, though operative, disclosing solution may be made, however, without using acetic acid. The disclosing solution may also contain a small amount of flavoring material, for example, oil of peppermint.

My preferred disclosing solution contains the following ingredients in approximately the following proportions by weight:

	Parts
Rose Bengal	45
Guinea Green B	4
Glycerine	15
Acetic acid	1
Water	600 50

In using the disclosing solution, it is applied to the teeth with a small brush or a wad of cotton, is allowed to remain on the teeth for a few seconds, and the mouth is then rinsed out with water in order to remove the excess disclosing solution.

Those parts of the teeth which contain stains are reacted upon by the disclosing solution, rendering them clearly visible. The teeth are then cleaned in the ordinary manner in order to remove the stains. If, due to inefficient cleaning of the teeth, some of the stains are left on them, the color on the stains disappears within a few hours.

Although I have given a preferred example of my disclosing solution, it is to be understood that the invention is not limited thereto, but may be otherwise embodied or practiced within the scope of the following claims.

I claim:

- 15 1. A disclosing solution for application to the teeth, containing Guinea Green B.
2. A disclosing solution for application to the teeth, containing Rose Bengal.
3. A disclosing solution for application to the teeth, containing Guinea Green B and Rose Bengal.
- 20 4. An aqueous disclosing solution for application to the teeth, containing Guinea Green B, Rose Bengal, and an agent for increasing the viscosity of the solution, the coloring ingredients being readily soluble in water and easily removed
- 25

by water from an applicator used in applying the disclosing solution to the teeth.

5 5. An aqueous disclosing solution for application to the teeth, containing Guinea Green B, Rose Bengal, and glycerine, the coloring ingredients being readily soluble in water and easily removed by water from an applicator used in applying the disclosing solution to the teeth.

6. An aqueous disclosing solution for application to the teeth, containing Guinea Green B, 10 Rose Bengal, glycerine and acetic acid, the coloring ingredients being readily soluble in water and easily removed by water from a applicator used in applying the disclosing solution to the teeth.

15 7. An aqueous disclosing solution for application to the teeth, containing the following ingredients in about the proportions specified by weight: Rose Bengal, 6 parts; Guinea Green B, 4 parts; glycerine, 15 parts; acetic acid, 1 part; 20 water, 600 parts, the coloring ingredients being readily soluble in water and easily removed by water from an applicator used in applying the disclosing solution to the teeth.
